Inventor
FRANK C. DORMENT.
By *Robert H. Smith*
Attorney

UNITED STATES PATENT OFFICE.

FRANK C. DORMENT, OF DETROIT, MICHIGAN, ASSIGNOR OF ONE-HALF TO GEORGE J. LOWE, OF CLEVELAND, OHIO.

AIR-CHARGING DEVICE.

1,309,880.

Specification of Letters Patent.

Patented July 15, 1919.

Application filed October 24, 1918. Serial No. 259,559.

To all whom it may concern:

Be it known that I, FRANK C. DORMENT, a citizen of the United States of America, residing at Detroit, in the county of Wayne 5 and State of Michigan, have invented certain new and useful Improvements in Air-Charging Devices, of which the following is a specification, reference being had therein to the accompanying drawings.

10 My invention aims to provide a simple and inexpensive air charging device which may be in the form of a volatilizer or inhaling apparatus and may be advantageously used by the medical profession, particularly as a means for the prevention and 15 treatment of respiratory diseases. The device or apparatus may be further used for deodorizing, disinfecting, fumigating and general air purifying purposes, and it is in 20 this connection, that I have devised a portable device that can be located in private or public places as a means of combating the transmission of infectious diseases and 25 destroying or neutralizing of obnoxious or dangerous gases.

My invention particularly resides in a container for a liquid or matter possessing remedial properties, for instance a volatile liquid, as the oil of eucalyptus. Mechanical 30 means is associated with the container for converting the volatile liquid into a dry fluid, for instance air impregnated with the properties of the liquid, and this is accomplished by either passing air through the 35 liquid to extract such properties or causing air to contact with the liquid or matter. In either instance the mechanical means maintains a supply and circulation of beneficial impregnated air that will serve either 40 as a deodorant, disinfectant or remedy in connection with respiratory diseases.

My invention further aims to provide a durable, sanitary and electrically operated inhaling apparatus, wherein the parts are 45 constructed with a view of reducing the expense of manufacture and at the same time retain those features by which the apparatus may be easily regulated and present a neat appearance.

50 Reference will now be had to the drawing, wherein

Figure 1 is a side elevation of the apparatus;

Fig. 2 is a plan of a portion of the same;

Fig. 3 is a vertical sectional view of the 55 apparatus; and

Fig. 4 is a plan of the same with the motor and a portion of the fan casing removed.

In the drawings, the reference numeral 60 1 denotes a circular flanged base having a plurality of legs 2 or other supports and bolted or otherwise detachably connected to the base 1, as at 3, is the bottom 4 of a cylindrical container or receptacle 5, said 65 container having the cylindrical walls thereof provided with annular beads 6 and 7, the former limiting the seating movement of the container in the base 1, and the latter limiting the seating of the lid or cover 8 70 on the upper end of said container. The side wall of the container is also provided with an apertured boss 9 and connected to said boss is an adjustable shutter or valvular member 10 which is movable to and from 75 the apertured boss in order to regulate the volume of air which passes through the apertures of said boss into the container 5.

Mounted in the container 5 is an annular shell 11 in spaced relation to the 80 side walls of said container to form an annular chamber 12. The upper end of the shell 11 has a lateral flange 11^a soldered or otherwise connected to the walls of the container, adjacent its upper end, said flange 85 closing the upper end of the chamber 12 which receives air through the apertured boss 9. The lower end of the shell 11 is open and in spaced relation to the bottom of the container 5, so that air from the 90 chamber 12 may be drawn into said shell and during its passage through the apparatus become saturated or impregnated with a volatile or wood extracted liquid placed in the bottom of the container. The air 95 may be passed through the liquid or over the top thereof, according to its depth, quantity or location in the container, and the downward and then upward circulation of air is brought about by producing a 100 partial vacuum in the shell 11, as will hereinafter appear. In some instances, a solid or semi-solid medicinal preparation may be used and attacked by the air, particularly when a mild dry-air treatment is desirable. 105

The lid or cover 8 has a central opening affording an annular tapering seat 13 for the depending tapering connection 14 of a

sectional fan casing 15, said casing being composed of two horizontally disposed connected sections that provide a fan compartment or chamber directly above the connection 14 which communicates with the shell 11. The fan casing 15 has a tangentially disposed outlet connection 16 to receive a plug 17 in communication with a flexible hose or conduit 18 having its outer 5 end provided with a nose or mouth piece 19 of any conventional form.

Suitably mounted on the fan casing 15 is a variable speed electric motor 20 which has its armature shaft 21 extending axially of 15 the fan casing 15 and provided with a fan 22 within said casing said fan having its blades or vanes shaped to produce a suction or partial vacuum in the shell of the apparatus, so that fumes or impregnated air may 20 be withdrawn from the shell and discharged through the elements 16 to 19 inclusive. The motor 20 has a plug or electrical connection 23 so that it may be operated from an ordinary electric lighting circuit.

25 A detachable screen 25 may be mounted in the shell 11 to break up and disintegrate any particles of matter carried upwardly in the shell, thus contributing to the impregnation of air by the volatile liquid or matter in the container. The screen 25 may be suitably positioned and frictionally held by a spring or gripping device 26.

It is through the medium of the shutter or valvular member 10 that the degree of 35 air impregnation by the volatile liquid is regulated; it being possible to supply air at the nose or mouth piece 19 that is either rich or poor in its remedial properties, and through the medium of the variable speed 40 electric motor 20, which is of the ordinary and well known type, the speed of the fan 22 may be varied and consequently the volume and force of impregnated air to the outlet of the apparatus.

45 The apparatus in its entirety is finished to present a neat appearance for professional use, and while in the drawing there is illustrated the preferred embodiment of my invention, it is to be understood that the 50 structural elements are susceptible to such variations and modifications as fall within the scope of the appended claims.

What I claim is:—

1. An apparatus of the character described comprising a container adapted to receive air above the bottom thereof and hold a volatile liquid on the bottom thereof, a casing communicating with the top of said container having an outlet, and means in 55 said casing adapted to produce a partial vacuum in said container to cause air to 60

travel downwardly toward the bottom of said container and then upwardly through said casing.

2. An apparatus of the character described 65 comprising a container adapted to receive air, means carried by said container adapted to regulate the supply of air thereto, a shell in said container adapted to contain a volatile liquid and coöperate 70 therewith in providing an annular chamber, adapted to have air travel downwardly therein, a casing communicating with the top of said container and provided with an outlet, and an electrically driven variable 75 speed fan in said casing adapted to produce a partial vacuum in said container.

3. An apparatus of the character described comprising a container adapted to receive air, a valvular member carried by 80 the side of said container adapted to regulate the supply of air thereto, a shell in said container adapted to receive a volatile liquid and coöperate with said container in providing an annular air chamber, a cover on said 85 container, a fan casing supported by said cover and communicating with said container and the shell therein, said fan casing having an outlet, a conduit connected to the outlet of said fan casing, a fan in said 90 fan casing, and an electric motor on said fan casing adapted to operate and provide a variable speed for said fan casing.

4. An apparatus of the character described, comprising a container adapted to 95 receive air and hold volatile matter, said container having side air inlet openings, a shell in said container providing a chamber with its upper end closed and its lower end open into said container, and means on said 100 container adapted to cause air to circulate in said chamber and said shell.

5. An apparatus of the character described, comprising a container, a valvular member on the side of said container 105 adapted to admit air thereto, a shell in said container providing an annular chamber having its upper end closed and its lower end in proximity to the bottom of said container so that air admitted to said container 110 may pass downwardly under the lower edges of said shell, and means on top of said container communicating with said shell adapted to produce a circulation of air through said apparatus.

In testimony whereof I affix my signature in presence of two witnesses.

FRANK C. DORMENT.
